UNITED STATES PATENT OFFICE.

JAMES M. TAYLOR, OF DETROIT, MICHIGAN.

LOCK

1,350,392.

Specification of Letters Patent. Patented Aug. 24, 1920.

Application filed March 12, 1920. Serial No. 365,286.

To all whom it may concern:

Be it known that I, JAMES M. TAYLOR, a citizen of the United States, residing at Detroit, in the county of Wayne and State of Michigan, have invented certain new and useful Improvements in Locks; and I do hereby declare the following to be a full, clear, and exact description of the invention, such as will enable others skilled in the art to which it appertains to make and use the same.

This invention relates to locks, and aims to provide a lock of novel and improved construction, and using a screw threaded key for releasing the shackle or similar member.

A further object is the provision of a lock mechanism which can be contained within a small barrel or case, and the working parts of which are so arranged as to prevent the possibility of the lock being picked or opened without the aid of the required key.

Another object is the provision in the lock of a guard or barrier which prevents the operation of the lock for opening it, until such guard or barrier is actuated by the key.

A still further object is the provision of such a lock embodying two correlated movable parts, one to engage the shackle or similar member, and the other normally operable to prevent the first named member from being moved to releasing position, such members being controlled by a key having separate threaded or equivalent portions for first moving the second named member in order that the first named member can then be moved to releasing position.

Another object is the provision of a novel key for operating the lock, embodying independently-operable members, one for preparing the lock so that the other can be manipulated to open the lock.

With the foregoing and other objects in view, which will be apparent as the description proceeds, the invention resides in the construction and arrangement of parts hereinafter described and claimed, it being understood that changes can be made within the scope of what is claimed without departing from the spirit of the invention.

The invention is illustrated in the accompanying drawings, wherein:

Figure 1 is a longitudinal median section of the lock shown in the form of a padlock, portions being shown in elevation.

Fig. 2 is a section on the line 2—2 of Fig. 1.

Fig. 3 is a section on the same line as Fig. 2 showing the key inserted and manipulated to open the protective guard or barrier so that the lock can be opened.

Fig. 4 is an end view, with the near end plate of the case removed.

Fig. 5 is a side elevation of a modification, portions being broken away and shown in section.

In the embodiment of the invention as shown in Figs. 1, 2, 3 and 4, the improvements are incorporated in a padlock, although they can be used in other types of locks. The lock embodies a cylindrical barrel or case 7 having the end plates 8 and 9 secured to the ends thereof by means of screws 10 or the like. The shackle 11 of the padlock has one end pivoted, as at 12, to the end plate 9, and its other end portion 13 is movable through an opening 14 in the case 7 near the opposite end. The free terminal or end portion 13 of the shackle has a notch 15 and a lug 16, said lug being formed with a cam face 17.

A detent 18 is slidable longitudinally within the case, being provided with longitudinal ribs 19 on its periphery at one end 85 slidable within longitudinal grooves 20 in the interior surface of case whereby to prevent said detent from rotating within the case. This detent has means for the engagement of the free terminal 13 of the shackle, 90 and for this purpose, the outer end of the detent has a recess 21 centrally thereof, and a slot 22 extending radially from the recess to the opening 14. Said slot 22 permits the passage of the free terminal 13 of the shackle, so that the lug 16 can lock within the recess 21, as seen in Fig. 1. The detent has a shoulder 23 and a coiled expansion spring 24 surrounding the detent is confined between said shoulder and an inner 100 annular collar 25 with which the case 7 is provided between the ends thereof, thereby moving said detent toward the end plate 8 so as to remain in engagement with the shackle. When the portion or terminal 13 105 of the shackle is moved through the opening 14, the cam face 17 will force the detent inwardly against the tension of the spring 24, causing said detent to snap into engagement with the notch 15 and lug 16.

The inner end portion of the detent is slidable within the collar 25, while the outer en-

larged end portion, which is provided with the ribs 19, is slidable within the case. The inner end of the detent 18 has a screw threaded hole 26 for the engagement of the key used in retracting the detent for releasing the shackle.

The key has a central stem 28 provided with a screw threaded tip 27 to engage with in the threaded hole or portion 26 of the 10 detent, and the opposite end of the stem 28 has a finger piece 29, for turning said stem, whereby the tip 27 in screwing into the hole 26 will enable the detent to be retracted to releasing position. Said part of the key is 15 for the purpose of opening the lock by moving the detent to releasing position, and the key has another part for first preparing the lock so that the detent 28 can be operated for the intended purpose. This second part 20 of the lock includes a tubular stem 39 mounted for rotation and sliding movement on the stem 28, and screw threaded on the exterior that end of the stem 39 nearest the finger piece 29 also having a suitable finger piece 25 42 with a shoulder 41 to bear against or abut the end plate 9. The threaded tip 27 of the stem 28 projects from the stem 39 so as to enter the hole 26 with the finger piece 29 bearing against the finger piece 42, as seen in 30 Fig. 3.

The lock is provided with a protective guard or barrier to prevent the stem 28 being moved into engagement with the detent unless the guard or barrier is first opened or 35 released, thereby preventing a single threaded stem or similar implement from being used for opening the lock or picking same. This guard or barrier comprises leaf springs 31 (two being used as shown) which are 40 fitted in longitudinal grooves 31 in the detent 18 under or within the spring 24, which serves to retain said leaf springs in place. The leaf springs have terminals 32 projecting from the rear or inner rounded end of 45 the detent, and forming the guard or barrier members. Said guard members or terminal fingers 32 have a tendency to spring apart, as seen in Fig. 3, and can be sprung toward one another, so as to close the guard or barrier in front of the threaded hole or 50 recess 26, as seen in Fig. 2, thereby preventing a key or implement from entering the threaded hole 26 of the detent.

A cylindrical slide or member 33 is movable within the case at that end opposite to the end in which the detent is movable, and is similarly prevented from turning in the case, said slide 33 having longitudinal ribs 34 on its periphery working within longitudinal grooves 35 in the case. The slide 33 is moved inwardly toward the detent by means of a coiled expansion spring 36 confined between the outer end of said slide and the end plate 9, and the inner end of the slide 60 has a concaved cam recess 37 which, in en-

gaging the guard members or fingers 32, will bring them toward one another into contact, as seen in Fig. 2. When the slide 33 is released, the expansion of the spring 36 will move said slide against the collar or abutment 25, thereby forcing the members 32 toward and against one another in front of the threaded hole 26 to close the guard or barrier. The slide has a screw threaded bore or hole 38 for the engagement of the threaded sleeve 39 of the key, and the end plate 9 has an opening or aperture 40 for the sliding passage of said tubular sleeve 39.

When the key is removed, so as to release the detent and slide or member 33, the detent is moved against the end plate 8 by the spring 24, and the slide 33 is moved against the collar 25 by the spring 36, and this will close the guard or barrier and the shackle can be snapped into engagement with the detent when forced into the case, the slide 33 moving with the detent when the cam 17 forces the detent away from the end plate 8, after which the parts return thereby locking the shackle within the case. The pressure of the slide 33 against the guard members 32 will hold them closed, thereby preventing the lock being opened without the required key, inasmuch as the detent can not be engaged for moving it to releasing position, as long as the guard is closed. However, with the provision of a key as shown in Fig. 3, the lock can be readily opened. This is done by first sliding the tubular stem through the aperture 40, the stem 28 moving with it into the bore 38, and the sleeve 39 is then rotated so as to screw into the bore 38 and when the shoulder 41 abuts the end plate 9, the slide 33 will then be moved outwardly from the center of the case against the tension of the spring 36 as seen in Fig. 3, removing said slide from the guard members 32 which will now spring open away from one another. The stem 28 can now be slid inwardly to screw the tip 27 thereof into the detent, and when the finger piece 29 abuts against the finger piece 42, the screw action will retract the detent from the shackle, so that the shackle can be swung open. The key can then be removed by first unscrewing the stem 28 and then unscrewing and withdrawing the sleeve 39, which will release the detent 18 and slide 33 in turn, so that they will resume their normal positions as seen in Fig. 2.

With the arrangement as above described, 120 the lock requires a special key having two independently rotatable threaded stems of proper pitch and size, and key changes can be provided by using screw threads of different pitches and changing the proportions 125 of the parts as will be readily understood by those skilled in the art. By the provision of the guard or barrier, it is practically impossible to open the lock without the aid of a proper key, and the lock has but 130

few working parts, so that it is simple in construction and operation.

The improvements can be used in other styles of locks, as suggested in Fig. 5, where-
5 in a member 11' has a terminal 13' to enter the case for the engagement of the detent, illustrating how the lock mechanism can be used for holding other members besides the shackle of a pad lock.

10 Having thus described the invention, what is claimed as new is:—

1. A lock comprising in combination, a detent, a guard for the detent, means controlling the guard, and a key having two relatively movable members, one having means for operating said means to control the guard, and the other having means to operate the detent when the guard is operated by the first named member.

20 2. A lock comprising a detent, a guard for the detent, a spring-pressed member for moving the guard to protective position, and a key having two relatively movable members, one of said members having means for operating said spring-pressed member to open the guard and the other member having means for moving the detent when the guard is opened.

30 3. A lock comprising in combination, a detent, a spring guard, a spring-pressed member movable to bring said guard to protective position, and a key having relatively movable members, one of which is engageable with said spring-pressed member to move it for opening the guard and the other member having means for moving the detent, said detent and members being movable longitudinally.

40 4. A lock comprising a detent having means at one end for the engagement of a key, spring guard members at such end of the detent, and a spring pressed member movable toward said detent and having a cam for moving said guard members toward one another, to prevent the key engaging said detent, said member having a hole for the passage of the key and for retracting said member by the key.

50 5. A lock comprising in combination, a detent, a member having a threaded bore, a guard controlled by said member, and a key having relatively movable threaded members, one to engage in the bore of said member for controlling the guard, and the other to threadedly engage the detent for moving it.

60 6. A lock comprising in combination, a detent having a threaded hole, a spring guard for said hole, a spring-actuated member for moving said spring guard to protective position in front of said hole, and a key having relatively movable screw threaded stems, said spring-actuated member having a threaded bore for the engagement of

one stem for moving said member to open 65 the guard and the other stem being engageable with the detent in said hole thereof for moving the same.

7. A lock comprising a detent having a threaded hole at one end for the engagement 70 of a key, spring guard members at said end of the detent, a member having a cam for moving said guard members toward one another to prevent the key entering said hole, said member having a threaded bore 75 for the passage and engagement of the key, and spring means for moving said member toward the detent to move said guard members toward one another.

8. A lock comprising a case having an 80 aperture at one end, a detent slideable within the case near the opposite end, said detent having a threaded hole at that end nearest said aperture for the engagement of a key, spring means for moving said detent away 85 from said aperture, a member slideable within the case between said aperture and detent, spring guard members within the case projecting between said detent and member, said member having a cam for moving said 90 guard members toward one another to prevent the key entering said threaded hole, said member having a threaded bore for the engagement and passage of the key, and spring means for moving said member away 95 from said aperture.

9. A lock including in combination, two relatively movable screw threaded members, one controlling the other, and a key having a pair of independently operable screw 100 threaded stems for moving said members.

10. A lock comprising in combination, a pair of relatively movable members having screw threads, a key having screw-threaded stems mounted one on the other to engage 105 the respective members, and means preventing one stem from engaging the corresponding member until the other member is moved by the other stem.

11. A lock comprising in combination, 110 two relatively movable members having screw threads, a key having a threaded stem to engage one of said members and a tubular threaded stem rotatable and slideable on the first named stem to engage the other 115 member, and means operated by one of said members for preventing the other member being engaged by the corresponding stem until the other stem has moved the corresponding member.

12. A lock comprising in combination, a detent, a slideable member, said detent and member each having screw threads, a key having a stem with screw threads and a tubular stem slideable and rotatable on said 125 stem and screw threaded, the first and second named stems being engageable with the detent and member respectively, and means

- 4
- preventing the first named stem from engaging the detent until said member is retracted by the tubular stem.
13. A lock comprising in combination, a case having an aperture at one end, a detent 5 slideable in the case having a threaded hole, spring means for moving said detent away from said aperture, a spring guard, a member slideable in the case between said aperture and detent and movable toward said 10 detent for moving said guard in front of said hole, said member having a threaded bore, spring means for moving said member toward the detent, and a key having 15 a stem with a threaded end to engage in said hole, and a tubular threaded stem slideable and rotatable on the first named stem to pass through said aperture and engage in said bore for retracting said 20 member and releasing said guard.
14. A key embodying a stem and a tubular stem thereon, each of the stems having a finger piece and screw threads for operating a member of a lock.
15. A key comprising a stem and a tubular 25 stem rotatable and slideable thereon, said tubular stem being screw threaded and having a finger piece, and the first named stem having screw threads beyond the screw threaded portion of a tubular stem and a 30 finger piece beyond the aforesaid finger piece.

In testimony whereof I have signed my name to this specification in the presence of two subscribing witnesses.

JAMES M. TAYLOR.
